ELECTRIC LIGHT BULB DEVICE

Filed Aug. 13, 1930

Fig. 2.

Roy J. Finesey,
INVENTOR

Victor J. Evans
ATTORNEY

UNITED STATES PATENT OFFICE

ROY J. FINESEY, OF OTTUMWA, IOWA

ELECTRIC LIGHT BULB DEVICE

Application filed August 13, 1930. Serial No 475,039.

This invention relates to means for removing and replacing electric light bulbs which are inaccessible from the floor, except through means of a ladder or the like, the general object of the invention being to provide a supporting member of considerable length and having a vacuum cup at its upper end for holding a bulb, with means for imparting movement to the cup from a point adjacent the lower end of the supporting means so that the electric light will be unscrewed from its socket or screwed therein while being held by the cup.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

25 Figure 1 is an elevation of the device.

Figure 2 is a section on line 2—2 of Figure 1.

Figure 3 is a view of the structure intersected by line 3—3 of Figure 1.

30 Figure 4 is a view of the structure intersected by line 4—4 of Figure 1.

In these views, the numeral 1 indicates a strip or supporting member of considerable length. A bracket 2 is held to the lower part 35 of the strip by the bolt 3 and this portion of the strip is provided with a number of holes 4 through any one of which the bolt can be passed so that the bracket can be adjusted lengthwise on the strip. A bracket 5 is fastened to the top part of the strip by the bolt 6 and a sectional shaft 7 is rotatably supported in these brackets. The upper end of the shaft passes entirely through the bracket 5 and the lower end extends 40 through the top part of the bracket 2. The sections of the shaft are detachably connected together by the couplings 8 so that the length of the shaft can be adjusted by removing certain sections or adding sections. A toothed wheel 9 is journaled on an extended part of

the bolt 3 and a handle 10 is connected to said gear.

A pinion 11 is fastened to the lower end of the shaft 7 and meshes with the gear 9 so that when the gear 9 is rotated, the shaft 55 will also be rotated. The upper end of the shaft 7 carries a chuck 12 which acts to hold a vacuum cup 13, said chuck being illustrated as of a standard commercial type and therefore tapered and subject to movement longitudinally of its main axis to operative position. A toothed wheel 14 is rotatably supported by the upper bracket 5, as shown at 60 15, and a pinion 16 on the upper part of the shaft 7 meshes with the toothed wheel 14 so that the rotary movement of the shaft is imparted to the wheel 14.

A stub shaft 16 is journaled in the upper bracket 5 and extends at right angles from the strip 1 and carries a pinion 17 which meshes with the toothed wheel 14 so that said stub shaft is rotated when the shaft 7 is rotated. The shaft 16 carries a chuck 18 for holding a vacuum cup 19. By providing the chucks for holding the vacuum cups, different sizes 70 of cups can be placed in the chucks in accordance with the size of the electric bulbs to be handled.

When the device is to be used to remove or replace a bulb which depends from a ceiling or the like, the cup 13 is used, the cup being placed in engagement with the bulb and then by turning the handle 10, the gears 9 and 11 will cause the shaft 7 to be turned 80 so that the cup 13 will be rotated in one direction or the other, according to the direction of movement of the handle 10 and thus the bulb can be screwed into its socket or 85 screwed out of the socket. When the bulb extends horizontally or at an angle and it is impossible to handle the same by the top cup, the horizontal cup 19 can be used, this cup being rotated through the gears 14, 16 and 17 from the shaft 7.

Thus I have provided simple means for enabling one to remove and replace bulbs which are at such a height that a person standing on the floor cannot reach the same.

It is thought from the foregoing descrip- 100

tion that the advantages and novel features of the invention will be readily apparent.

It is to be understood that changes may be made in the construction and in the combination and arrangement of the several parts, provided that such changes fall within the scope of the appended claims.

What I claim is:—

1. A device of the class described comprising an elongated supporting strip, upper and lower brackets connected therewith, means whereby the lower bracket can be adjusted lengthwise on the supporting strip, a sectional shaft journaled in the brackets with the upper end of the shaft projecting beyond the upper end of the strip, means for detachably connecting the sections of the shaft together, a toothed wheel rotatably supported by the lower bracket, a pinion on the shaft engaging the toothed wheel, a handle for turning the wheel, a chuck connected with the upper end of the shaft and a vacuum cup carried by the chuck.

2. A device of the class described comprising an elongated supporting strip, upper and lower brackets connected therewith, means whereby the lower bracket can be adjusted lengthwise on the supporting strip, a sectional shaft journaled in the brackets with the upper end of the shaft projecting beyond the upper end of the strip, means for detachably connecting the sections of the shaft together, a toothed wheel rotatably supported by the lower bracket, a pinion on the shaft engaging the toothed wheel, a handle for turning the wheel, a chuck connected with the upper end of the shaft, a vacuum cup carried by the chuck, a stub shaft journaled in the upper bracket and extending horizontally, a toothed wheel journaled in the upper bracket, pinions on the upper end of the shaft and on the stub shaft meshing with the wheel of the upper bracket, a chuck carried by the stub shaft and a vacuum cup carried by said chuck.

In testimony whereof I affix my signature.
ROY J. FINESEY.
